UNITED STATES PATENT OFFICE.

NETTIE A. LUM, OF CARNEIRO, KANSAS.

MEDICAL COMPOUND.

SPECIFICATION forming part of Letters Patent No. 291,751, dated January 8, 1884.

Application filed June 4, 1883. (No specimens.)

To all whom it may concern:

Be it known that I, NETTIE A. LUM, of Carneiro, in the county of Ellsworth and State of Kansas, have invented certain new and useful Improvements in Medical Compounds; and I do hereby declare the following to be a full, clear, and exact description of the invention, such as will enable others skilled in the art to which it pertains to make and use the same.

My invention relates to a medical compound to be used either as a liniment or as an internal remedy for the cure of rheumatism, neuralgia, and analogous diseases, the object being to provide a compound of this character which shall be thoroughly effective.

My compound consists in the following ingredients, combined in the proportions stated, viz: alcohol, one pint; oil of peppermint, two drams; oil of sassafras, two drams; oil of spearmint, two drams; oil of origanum, one ounce; oil of hemlock, one ounce; oil of turpentine, one dram; oil of capsicum, one dram; gumcamphor, one ounce. These ingredients should be thoroughly mixed by agitation, and the bottle kept tightly corked.

In using the above-specified compound the dose for adults should be from eight to ten drops three times a day, and for children from one to eight drops.

What I claim, and desire to secure by Letters Patent, is—

The herein-described compound, consisting of alcohol, oil of peppermint, oil of sassafras, oil of spearmint, oil of origanum, oil of hemlock, oil of turpentine, oil of capsicum, and gum-camphor, in substantially the proportions specified.

In testimony whereof I have signed this specification in the presence of two subscribing witnesses.
